UNITED STATES PATENT OFFICE.

WILLIAM H. CLARK, OF WHITTIER, CALIFORNIA.

PULLER FOR PUMP LINERS AND VALVE SEATS.

Application filed August 27, 1924. Serial No. 734,422.

To all whom it may concern:

Be it known that I, WILLIAM H. CLARK, a citizen of the United States, residing at Whittier, in the county of Los Angeles and 5 State of California, have invented a new and useful Puller for Pump Liners and Valve Seats, of which the following is a specification.

This invention relates to means for pulling pump liners out of cylinders of pumps and also for pulling valve seats.

Mud pumps are employed in the drilling of oil wells for circulating mud through the well casings for the purpose of carrying 15 away the detritus loosened by the drill steels and the pumps hold the pressure on the wells so that the drilling operation can be continued when there is considerable gas pressure in the wells.

20 Because of the character of the fluid on which the pump operates and the necessarily high pressures employed, the mud works between the liner and the cylinder and solidifies there, thus causing sticking of the liner 25 in the cylinder. It follows that the liners of mud pumps and also of deep well pumps are particularly difficult to pull from the pump cylinders and barrels when it becomes necessary to substitute new liners for the old 30 ones due to wear occasioned by the pumping operation. Ordinarily, the pulling of the liners of mud pumps requires several hours, thus entailing considerable labor, expense and loss of the use of the pump during that 35 time.

An object of this invention is to quickly effect the pulling of pump liners and valve seats when it becomes necessary to substitute new ones therefor.

40 Another object is to effect the pulling of the liners and valve seats by engaging the inner ends thereof, the effect being to push the liners out of the cylinders.

To effect the foregoing, there is provided 45 a means insertable through the liner or valve seat and expandable to engage the inner end of said liner or valve seat, and means to exert a pull on the insertable means.

The accompanying drawings illustrate the 50 invention:

Figure 1 is a longitudinal section of a 55 typical mud pump, showing two pullers embodying the invention in operative position on the pump, one puller being in position for pulling the liner and the other being in position for pulling the valve seat.

Fig. 2 is a fragmental elevation, partly in section, from the line indicated by 2-2, Fig. 1.

Fig. 3 is an end view of the expandable 60 unit or collapsible jaws of the puller, the view being taken looking at the liner-engaging end of the jaws.

A fragment of a mud pump is shown in Fig. 1, there being a cylinder 4, a liner 5 in 65 said cylinder, packing 6 between the cylinder and the liner, and stud bolts 7 for holding the cylinder head, not shown, secured in place on the cylinder. Also the mud pump is provided with the customary valve seats 8. 70

75 Expansible means of suitable construction, indicated in general by the character 9, are inserted through the liner or valve seat, as the case may be, to engage the liner when said means are expanded. In this particular instance the expandible means project beyond the inner ends of the liner or valve seat and comprise a unit made up of a number of collapsible jaws 10 connected with a feed screw 11 which passes through 80 a hole 12 in a support 13 and projects beyond said support. The projecting end of the screw 11 has thereon a nut 14 which engages screw threads 15 of the screw and the support 13 functions as an abutment to resist pressure of the nut 14 when said nut is turned to force the screw 11 outwardly.

85 Each of the jaws 10 has a threaded portion 16 engaging screw threads 17 of the screw 11. In this particular instance there are four jaws 10 and, when they are assembled, the threaded portions 16 together substantially form a circle at the ends of the jaws where the screw 11 enters, and the jaws are reduced outwardly so that when 90 the screw 11 is backed out of the jaws the free ends of the jaws can readily collapse toward one another so as to reduce the diameter of the jaw unit at the free ends thereof, as when it is desired to pass the jaws through the liner or valve seat. The screw 11 constitutes one form of means for wedging the jaws outwardly to the expanded positions. It is desirable to provide grooves 95 100 105 110

115 said jaws, the inner ends being those where the screw 11 enters the jaw unit. In the grooves 18 is seated a circular spring 19 which holds the jaws in engagement with the screw threads 17 and also collapses the jaws when the screw 11 is backed out until the screw barely engages said jaws.

The free ends of the jaws 10 are provided on their outer faces with shoulders 20 which are adapted to engage the inner end of the liner 5 or valve seat 8, as the case may be, 5 to effect removal thereof.

To pull the valve seat 8 the screw 11 will be backed out of the jaws until only the very tip of the threaded portion engages said jaws. When this is done the spring 19 will 10 cause the jaws 10 to collapse and hold them in such condition. Then the jaws will be inserted in the valve seat 8 sufficiently far to bring the shoulders 20 beyond the inner end of the valve seat, whereupon the screw 15 11 will be turned to expand the jaw unit, thus bringing the shoulder 20 in alinement with the inner end of the valve seat. Then the nut 14 will be turned to force the jaw unit outwardly, thus engaging the shoulders 20 20 with the valve seat and forcing said seat out of the opening 21 which the valve seat normally engages.

When the puller is employed to pull the liner 5, a ring 22 will be placed over the 25 stud bolts 7 in place of the cylinder head, not shown, and said ring is provided with a number of outstanding spacers 23 which are secured at their outer ends by nuts or other suitable means to the support 13. 30 These spacers 23 are necessary when pulling the liner in order to hold the support 13 a sufficient distance from the cylinder to accommodate the liner between the cylinder and the support 13 when it is pulled out of 35 said cylinder. The actual operation of pulling the liner is the same as described above for pulling the valve seat and, therefore, a

further description of the operation, is unnecessary.

I claim:

1. A puller of the character described comprising an expansible unit formed from a number of separate jaws, said jaws having threaded portions substantially forming a circle at one end of the expansible 45 unit, the jaws being reduced toward the other end of the unit, a screw engaging the screw threads, a support, a nut on the screw engaging the support, the smaller ends of the jaws having shoulders to engage the 50 member that is to be pulled, and means to hold the jaws assembled on the screw.

2. A puller of the character described comprising an expansible unit formed from a number of separate jaws, said jaws having threaded portions substantially forming a circle at one end of the expansible unit, the jaws being reduced toward the other end of the unit to permit collapsing thereof, a 55 screw engaging the screw threads, a support, a nut on the screw engaging the support, the smaller ends of the jaws having shoulders to engage the member that is to be pulled, there being grooves in the outer faces 60 of the jaws near the larger ends of said 65 jaws, and a circular spring seated in the grooves and operating to collapse the jaws when the screw is backed out so as to engage only the portion of the jaws between the grooves and the larger end of the jaws. 70

Signed at Los Angeles, California, this 20th day of August, 1924.

WILLIAM H. CLARK.
